UNITED STATES PATENT OFFICE.

EDDY PALMER, OF NEW YORK, N. Y., ASSIGNOR TO SOLON PALMER, INC., OF NEW YORK, N. Y.

DESIGN FOR A BOTTLE OR SIMILAR RECEPTACLE.

42,516.

Specification for Design.

Patented May 14, 1912.

Application filed January 24, 1912. Serial No. 673,258. Term of patent 14 years.

To all whom it may concern:

Be it known that I, EDDY PALMER, a citizen of the United States, residing in the city of New York, borough of Manhattan, in the county and State of New York, have invented a new, original, and ornamental Design for Bottles or Similar Receptacles, of which the following is a specification, reference being had to the accompanying drawing forming a part thereof.

Figure 1 is a perspective view of my new design showing the front of the bottle; and Fig. 2 is a similar view showing the rear of the bottle.

I claim:

The ornamental design for a bottle or similar receptacle as shown.

EDDY PALMER.
